United States Patent Office

Des. 191,941
Patented Dec. 19, 1961

191,941

DATA TRANSMITTER HOUSING OR SIMILAR ARTICLE

Laurin L. Sevebeck, Mountainside, N.J., assignor to Western Electric Company, Incorporated, New York, N.Y., a corporation of New York

Filed Mar. 20, 1961, Ser. No. 64,478

Term of patent 14 years

(Cl. D26—5)

Des. 191,941

PAGE 2

FIG. 3

FIG. 4

FIG. 5

FIG. 1 is a front perspective view of a data transmitter housing or similar article illustrating my new design.

FIG. 2 is a right side elevational view thereof, to a reduced scale;

FIG. 3 is a top plan view, to a reduced scale;

FIG. 4 is a front elevational view thereof, to a reduced scale; and

FIG. 5 is a perspective view looking at the rear, bottom and left side thereof.

I claim:

The ornamental design for a data transmitter housing or similar article, as shown.
